A. C. HULBERT

ELECTRIC HOT WATER HEATER

Filed Oct. 17, 1921

UNITED STATES PATENT OFFICE.

ANSEL C. HULBERT, OF SAN CARLOS, CALIFORNIA.

ELECTRIC HOT-WATER HEATER.

Application filed October 17, 1921. Serial No. 508,174.

To all whom it may concern:

Be it known that I, ANSEL C. HULBERT, a citizen of the United States, residing at San Carlos, in the county of San Mateo, State 5 of California, have invented a new and useful Electric Hot-Water Heater, of which the following is a specification, in such full and clear terms as will enable those skilled in the art to construct and use the same.

10 This invention relates to an electrical hot water heater and its object is to provide an automatic hot water heater which is capable of maintaining a supply of hot water at all times and which is self regulating.

15 Another object of the invention is to provide means whereby the electric current used to heat the water is capable of being broken with a step by step movement, whereby a smaller breaking gap is possible than if the 20 current were taken off all at one time.

A further object of the invention is to provide an apparatus which will be completely insulated so as to reduce the heat loss by radiation or conduction to the minimum.

25 A further object of the invention is to provide an electrical heater which is capable of being installed on any kitchen boiler without the use of special apparatus, the water heating chamber and regulating chamber being a self-contained unit separate from the 30 storage reservoir.

Other objects of the invention will appear as the description proceeds.

An embodiment of the invention is shown 35 in the accompanying drawings in which the same reference numeral is applied to the same portion throughout, but I am aware that there may be modifications thereof.

Fig. 1 is a side elevation of a boiler showing this heater installed in connection therewith.

Fig. 2 is a vertical sectional view through the heater illustrating diagrammatically the wiring used in conjunction therewith.

45 Fig. 3 is a front elevation of the regulating apparatus with the protecting cover removed.

Fig. 4 is a diagrammatic plan of the complete wiring system.

50 Fig. 5 is a diagrammatic elevation of the regulating apparatus showing the application of the circuit wires thereto, and

Fig. 6 is a view partly in longitudinal section of the complete regulating apparatus.

55 The ordinary kitchen boiler is indicated at

1. This has the supply pipe 2 and hot water pipe 3 connected therewith at the top.

On the side of the boiler there is a pipe 4 which extends to the water heating chamber 5, and a pipe 6 extends from the bottom of 60 the water heating chamber into the bottom of the water, a pipe 7 provided with the faucet 8 being used for cleaning the boiler whenever that is necessary.

The heating chamber consists of a rectangular cast iron box of such height as may be convenient to receive a plurality of electrical heating tubes 9 to 12 inclusive. Two of these tubes are installed from the right hand side of the heating chamber and are 65 carried by plugs 13 and 14, while the other two tubes are carried by plugs 15 and 16 screwed into the other side of the water heater.

Near the bottom of the water heater there 70 is the regulator 17. This regulator has a tube 18 which has any suitable thermostat element contained therein capable of moving the diaphragm 19. The diaphragm covers a flange 20 and is held in place against the 75 same by means of the flange 21, suitable screws 22 being used for this purpose.

The diaphragm has a button 23 secured thereto which bears upon one end of a pin 24, said pin extending through a bearing 25 supported by the flange 21. A stiff spiral spring 26 bears upon the diaphragm 19 and against the material within the tube 18 the 80 necessary pressure for properly operating the pin.

Two ears 29, 30 support a depending lever 31, the pin 24 bearing upon said lever for its operation. It is provided with an insulating tube 32 which is extended to bear upon all of the contact making arms 33 to 95 36 inclusive. These arms are secured to a bar 37 suitably insulated, screws being used to hold the bar and arms in place, and when the temperature is sufficiently reduced the liquid within the tube 18 will contract sufficiently to allow all of the contact making arms to contact with the screws 40, of which there are four, one for each contact arm.

A wire 41 leads to the binding post 42 on the fiber block 43 at the lower portion of the flange 21, and from this point suitable connections are made with the lower ends of the contact arms by means of the wire 44 and bar 37.

The adjustment of the electrical connec- 110

tions is effected by means of the four screws 40, the adjustment being such that one heating circuit will be broken at a time, and the entire series of four circuits will remain off so long as the heat in the lower part of the heating receptacle 5 is at the maximum required.

The boiler is completely enclosed with a metal cover 45 filled with any sort of non-conducting heating material as illustrated at 46, and similarly the heater itself is covered with a suitable thick layer of non-conducting material to prevent the loss of heat from the boiler by radiation or conduction.

The wiring circuit is shown in Figure 4, in which 50 represents the source of electric current from which the wire 41 leads to the bar 37. This bar in turn is connected with the breaker arms 33 to 36 inclusive from which wires 51 to 54 inclusive lead to the self heating elements 18 to 16 inclusive.

What I claim is as follows but various modifications may be made in the construction shown in the drawings and above particularly described form, within the purview of my invention.

1. An electric heating apparatus comprising a hot water storage receptacle, means to supply said receptacle with water and to withdraw water therefrom, a heating receptacle, electric heating unit in said receptacle, pipes for connecting said receptacle with the storage receptacle at the bottom and at a point intermediate its bottom and top, a plurality of electric heating elements extending into said heating receptacle, a thermostat in the lower portion of said heating re-

ceptacle for controlling the current supplied to said heating elements, and means to break the current used step by step.

2. An electric heating apparatus comprising a hot water storage receptacle, pipes for supplying said receptacle with water and for withdrawing water therefrom, a heating receptacle, pipes extending from the bottom of the water receptacle to the bottom of the heating receptacle and from the top of the heating receptacle to a higher portion of the water receptacle, a plurality of electric heating elements extending into said heating receptacle, a thermostat in the lower portion of said heating receptacle, and means for breaking the current used in the electric heating elements one element at a time.

3. An electric heating apparatus comprising a hot water storage receptacle, pipes to supply water to and remove water from said receptacle, a heating receptacle, a pipe connecting the lower portion of said heating receptacle with the lower portion of the water storage receptacle, a pipe connecting the top of the heating receptacle with a higher portion of the water receptacle, a plurality of electric water heating units extending into said receptacle, a thermostat in the lower portion of said heating receptacle, a circuit breaker for each heating element, and means whereby the thermostat will operate said circuit breakers to break the circuits on the electric heaters one at a time.

In testimony whereof I have hereunto set my hand this 6th day of October, A. D. 1921.

ANSEL C. HULBERT.
